BY

baffle members 12 disposed in the passages between tubes 8. Baffles 12 are spaced from tubes 8 and crown sheet 6.

Each baffle member 12 is formed of a single metal sheet bent to form side walls 13 of triangular contour. The adjacent side 14 of the triangle (the lower edge of baffle 12) is placed in proximity to crown sheet 6. The opposite side of the triangle 15 (the right-hand side of the baffle as shown in Figure 1) is placed adjacent the inlet of heat exchanger 7. The side walls 13 form an opening 16 at the opposite side of the triangle through which air enters chamber 17 formed by side walls 13. Opening 16 is approximately the height of baffle 12. An opening 18 is provided in the bottom of baffle 12 adjacent crown sheet 6 and extends substantially the length of baffle 12. Baffle 12 occupies approximately one-half of the width of the air passage between adjacent tubes 8. While I have described baffles 12 as being of triangular contour for ease of manufacture, it will be understood the baffles may be of any desired geometrical contour provided the interior surface is designed to direct unheated portions of the air stream continuously against the crown sheet.

Baffles 12 are mounted by means of clips 19 upon metal bars 20 and 21. Bars 20 and 21 are welded to clips 19 adjacent opening 16. The baffle assembly formed by bars 20 and 21 and baffles 12 may be disposed in place in the air passages 9 by tack welding bars 20 and 21 to tubes 8 at each side of unit 3.

In many cases fin members 22 are disposed in air passages 9 to increase the amount of heat exchange surface thus aiding in cooling crown sheet 6. Fins 22 preferably are shaped to provide a greater area of heat exchange surface at the outlet of the unit as shown in Figure 1. Fins 22 may be provided with an upper edge which extends diagonally upward from the inlet edge of the fin to the outlet edge of the fin thus considerably increasing the area of fin surface at the outlet and assuring that fresh portions of air are brought into contact with the fin throughout its length. In such types of construction each baffle 12 may be provided with a slot 23 extending along the hypotenuse of the triangle through which fin 22 may extend when baffle 12 is in place in air passage 9. The fins 22 and baffles 12 cooperate to increase the cooling capacity of the air stream with regard to the crown sheet.

Fan 10 forces air within chamber 17 of baffle 12, such air being deflected downward and forward in the baffle until it is forced against the crown sheet 6. The air then passes through the spaces between the side walls 13 of baffle 12 and the crown sheet and moves forward to discharge side of the unit. In effect, portions of the entering air stream in successive streams are forced down to contact the crown sheet 6 at which point such air escapes from baffle 12 and moves up diagonally along the walls of the passage 9 thereby providing a positive flow of continuously fresh portions of air to the crown sheet to cool the same effectively. By continuously bringing unheated portions of the air stream in direct contact with the crown sheet, a preheated layer of air is not present permitting a far higher convective conductance. The air is being continuously displaced from the crown sheet by a new portion of air.

The present invention provides a gas fired unit heater having its capacity greatly increased at low cost. The limiting factor in design of a gas

fired heating unit with regard to capacity is the problem of adequately cooling the crown sheet; the baffles of the present invention permit such area to be cooled effectively thereby increasing capacity of the unit.

While I have described a preferred embodiment of my invention it will be understood my invention is not limited thereto since it may be otherwise embodied within the scope of the following claims.

I claim:

1. In a direct fired heater the combination of a casing having an inlet and an outlet, a burner, a combustion chamber having a crown sheet, a heat exchanger connected to the combustion chamber comprising a plurality of spaced tubes extending therefrom in the casing between the inlet and the outlet, a fan for moving an air stream through the passages between the tubes, and a baffle to direct unheated portions of the air stream delivered by the fan within the casing against the upper surface of the crown sheet to cool the same, said baffle having a baffling surface disposed in spaced, inclined relation with respect to the crown sheet with its end adjacent the inlet being disposed at a greater distance from the crown sheet than its end adjacent the outlet, said baffle comprising a member having triangular side walls, a top wall connecting the side walls and an opening at the inlet side of the heat exchanger extending substantially the height of the triangular side walls, a second opening at the base of the member adjacent the crown sheet extending substantially the length thereof, the top wall deflecting substantially unheated portions of the air stream against the upper surface of the crown sheet.

2. In a gas fired heater, the combination of a casing having an inlet and an outlet, a gas burner in the casing, a combustion chamber having a crown sheet, a heat exchanger connected to the combustion chamber comprising a plurality of spaced elements extending therefrom in the casing between the inlet and the outlet, a fan for moving an air stream through the passages between the elements, and a baffle arrangement disposed between adjacent elements and having a baffling surface disposed in spaced, inclined relation with respect to the crown sheet with its end adjacent the inlet being disposed at a greater distance from the crown sheet than its end adjacent the outlet to continuously direct fresh portions of the air stream passing through the heat exchanger against the upper surface of the crown sheet.

3. A heater according to claim 2, in which the baffle arrangement includes spaced bar members extending across the rear of the heat exchanger adjacent the inlet and a plurality of baffle members supported by said elements to direct fresh portions of the air stream drawn by the fan within the casing against the upper surface of the crown sheet to cool the same, each baffle member being disposed between adjacent elements and having a baffling surface disposed in spaced, inclined relation with respect to the crown sheet with its end adjacent the inlet being disposed at a greater distance from the crown sheet than its end adjacent the outlet.

4. A heater according to claim 3 in which each baffle member is spaced from the crown sheet.

5. In a gas fired heater, the combination of a casing having an inlet and an outlet, a gas burner in the casing, a combustion chamber having a

crown sheet, a heat exchanger connected to the combustion chamber comprising a plurality of spaced tubes extending therefrom in the casing between the inlet and the outlet, a fan for forcing an air stream through the passages between the tubes and a plurality of baffles disposed between adjacent tubes, each baffle having a baffling surface disposed in spaced, inclined relation with respect to the crown sheet with its end adjacent the inlet being disposed at a greater distance from the crown sheet than its end adjacent the outlet, each baffle comprising a triangular member having side walls, a top wall connecting the side walls and an opening at the inlet of the heat exchanger, the base of the triangle being placed in proximity to the crown sheet.

6. In a gas fired heater, the combination of a casing having an inlet and an outlet, a gas burner, a combustion chamber having a crown sheet, a heat exchanger connected to the combustion chamber comprising a plurality of spaced tubes extending therefrom in the casing between the inlet and the outlet, a fan for forcing an air stream between the passages between the tubes and a plurality of baffles disposed between adjacent tubes, each baffle having a baffling surface disposed in spaced, inclined relation with respect to the crown sheet with its end adjacent the inlet being disposed at a greater distance from the crown sheet than its end adjacent the outlet, each baffle comprising a member having triangular side walls, a top wall connecting the side walls and an opening at the inlet side of the heat exchanger extending substantially the height of the triangular side walls and a second opening at the lower side of the triangle formed by the side walls and the top walls in proximity to the crown sheet extending substantially the length of the triangle whereby successive portions of the air stream passing through the heat exchanger are forced within the baffle and against the top wall thereof by the fan and deflected against the upper surface of the crown sheet adjacent the outlet to cool the crown sheet.

7. A gas fired heater according to claim 6 in which each baffle is secured to an upper element and to a lower element, said elements extending across the entering air side of the heat exchanger and being fastened to the heat exchanger.

8. A gas fired heater according to claim 6 in

which fins are disposed between adjacent tubes, said fins extending through openings in the baffles.

9. A gas fired heater according to claim 8 in which the edges of the fins extend upward from the inlet edges of the fins to the outlet edges of the fins thereby increasing the areas of the fins throughout the length thereof.

10. In a gas fired heater, the combination of a casing having an inlet and an outlet, a gas burner in the casing, a combustion chamber having a crown sheet, a heat exchanger connected to the combustion chamber comprising a plurality of spaced tubes extending therefrom in the casing between the inlet and the outlet, a fan for forcing an air stream through the passages between the tubes, triangular baffle members disposed in said passages to deflect fresh portions of the air stream passing through the passages against the upper surface of the crown sheet to cool the same, each baffle having a baffling surface disposed in spaced, inclined relation with respect to the crown sheet with its end adjacent the inlet being disposed at a greater distance from the crown sheet than its end adjacent the outlet, each triangular member being formed from a single sheet bent to form side walls and a top wall connecting the side walls to receive air at the inlet side of the heat exchanger and to deflect such air downward against the crown sheet.

11. A gas fired heater according to claim 10 in which a baffle member occupies approximately one-half of the width of the air passage between adjacent tubes.
